UNITED STATES PATENT OFFICE

CORA P. OLSON AND HARRY L. EVANS, OF ROCHESTER, MINNESOTA

PROSTATECTOMY URINAL

Application filed May 23, 1929. Serial No. 365,339.

Our invention relates to urinals, particularly adapted for use by patients who are confined to bed, suffering with prostatic trouble.

In prostatic cases, previous to the operation for the removal of the prostate, patients are required to drink a large amount of water and a catheter is inserted into the urethra. After the operation, a suprapubic drainage may be made and a rubber tube is inserted into the bladder. In both instances, there is a continuous flow of urine.

The object of our invention is to provide a suitable urinal for such instances, and among the particular objects of our present invention is to provide a urinal for such purposes which cannot be tipped over by the patient; which is so enclosed as to prevent the bed clothes from dipping into the urinal or getting wet; which is constructed so as to permit a tube to be inserted into the container far enough so that it will not slip out and wet the clothing; which does not have sharp edges to dig into the patient; which does not catch on bed clothes; which can be placed conveniently between the legs of the patient without annoyance and which will fit under the sides of the body of the patient without inconvenience; which will not interfere with the arms resting on the sides of the body, or the movement of the patient; which is adapted to hold large quantities of urine and therefore give the nurse greater freedom of action; which is provided with an opening large enough to permit thorough cleaning; which is provided with a convenient hand hole which does not provide projections adapted to cut into the patient or catch on clothing.

These and other objects of our invention will be apparent from a perusal of the following specification when taken in connection with the accompanying drawings, wherein:

Figure 1 is a perspective view of our improved urinal;

Figure 2 is an end view thereof;

Figure 3 is a cross sectional view;

Figure 4 is a sectional view on line 4—4 of Figure 1 showing the overhanging wall at the end of the urinal.

Referring now to the drawings in detail, our improved urinal is preferably formed of

sheet metal, preferably enameled on its outside to present a smooth glossy surface. The vessel is formed so as to provide a flat broad base 2 which is preferably rectangular in area.

At one end, the wall 4 of the urinal rises abruptly from the broad base and inclines somewhat outwardly away from the vertical plane. The opposite end wall 6 inclines upwardly and inwardly at an angle of approximately 45 degrees. The two opposed side walls 8 and 10 likewise incline upwardly and inwardly substantially at an angle of 45 degrees. These walls 8 and 10 meet the end wall 6 to provide diagonal curved ridges 12 and 14 which converge at the point 16 to form a rounded ridge 18 along the top of the urinal. The ridges 12 and 14 are preferably concave. The side walls 8 and 10 gradually assume a concave formation which is most pronounced at the end thereof as shown by the curved lines 20 and 22 at the end wall 4. The purpose of these concave walls is to permit the urinal to fit snugly and easily between the legs of the patient and so as not to present any sharp edges to dig into the patient.

At the top of the urinal and at the end wall 4 thereof we provide a spout 24 of very generous proportions. This spout has one end 26 as a part of the upper portion of the end wall 4 and it will be noted that this portion 26 overlies the lower portion of the vertical wall 4 whereby to facilitate pouring out of the contents of the urinal. The spout 24 is somewhat oval in formation and extends in a direction toward the opposite end wall 6 whereby to facilitate the insertion of a drain tube and thereby retain the same in position. The metal at the edges of this nozzle 24 is turned back to provide a smooth, preferably rolled bead thereat. In addition, the large proportion of this spout permits facile cleaning of the interior of the urinal.

The two side walls 8 and 10 are provided with inwardly projecting integral walls 28 and 30 forming closed slots, one on each side of the rounded ridge 18, which slots form a hand grip or handle for the urinal. In the present illustration, these hand holes are formed by suitably indenting or depressing the walls 8 and 10 of the urinal.

From the foregoing description, it will be evident that we have provided a urinal which cannot be overturned by the patient due to the relatively broad base and the low squat characteristics of the urinal which include the upwardly inclined concave sides and the upwardly inclined end wall, all of which merge into the curved ridge at the top of the urinal. In addition, it will be evident that by forming the spout at the opposite end of the urinal and at a point where the end wall merges into the ridge, we are enabled to permit the emptying of the urinal with great speed and without spilling the contents while at the same time, we are enabled to provide a hole of sufficient size not only to facilitate the cleaning of the interior of the urinal but also to permit the entry and maintenance therein of the drainage tube. By reason of our improved construction of urinal having these flat smooth walls, which are wholly devoid of projections adapted to dig into the patient or catch on the clothes, and by reason of the curvilinear sides of the urinal adapted to fit the legs of the patient, we have provided a most compact and improved type of container for prostatic cases. Our improved urinal is quite sanitary since it will not permit the liquid to slop or spill out of the nozzle; will not turn over; will not permit the bed clothes to dip into the urinal; will securely hold the retaining tube in position; can be conveniently emptied; has no sharp edges to dip into the patient or cut bed clothes and can be placed between the legs or at the side of the patient without digging into or hurting him; will fit the sides of the body without inconvenience and does not interfere with the arms resting on the sides of the body nor with the movements of the body. In addition, it is adapted to hold a large quantity of urine. The device is simple in construction, easy to manufacture, and withal is a most improved prostatectomy urinal.

Having thus described our invention, what we claim is new and desire to secure by Letters Patent is:

1. A urinal particularly adapted for prostatic cases, having a relatively broad flat base and having two flat end walls, the one rising substantially vertically, and the other inclining upwardly and inwardly substantially at 45 degrees, said urinal having two side walls inclining upwardly and inwardly, substantially at 45 degrees and joining the two end walls, the juncture of the ridge and the substantially vertical end wall being cut away to provide a relatively generously sized emptying mouth.

2. A urinal having a relatively broad flat substantially rectangular base with upstanding walls inclining inwardly to form a closed top having smooth outer wall surfaces, said top being cut away at its juncture, with one

of the end walls, to provide an upstanding spout for the urinal.

3. A urinal having a relatively broad flat base with upstanding walls inclining inwardly to form a closed top having smooth outer wall surfaces, said top being cut away at its juncture with one of the end walls, to provide a spout for the urinal, the side walls of the urinal being curvilinear in formation to fit the body of the patient, said spout overhanging the one end wall at the base to facilitate in emptying the urinal. 75

4. A urinal having a relatively broad flat base with upstanding walls inclining inwardly to form a closed top having smooth outer wall surfaces and to form a ridge along a part of the top and longitudinal with the center line thereof, said top being cut away at its juncture with one of the end walls, to provide a spout for the urinal, the side walls of the urinal at the spout end being concave in formation. 80

5. A urinal having a relatively broad flat base with upstanding walls inclining inwardly to form a closed top having smooth outer wall surfaces, said top being cut away at its juncture, with one of the end walls, to provide a spout for the urinal, the side walls of the urinal at the spout end being concave, said concave formation extending over substantially the entire length of the side walls. 90

6. A urinal having a flat broad substantially rectangular base and upstanding walls forming a closed top, said top having an opening therein and an upstanding spout formed about the opening, certain of the upstanding walls of the urinal being concave to fit the body of the patient. 100

7. A urinal having a relatively broad base and relatively short upstanding walls forming a closed top and a longitudinal ridge, the top of said urinal being provided with an opening forming a spout, and the side walls of the urinal being provided with inwardly extending recesses or depressions on each side of the ridge for forming a hand grip. 105

8. A urinal having a relatively broad flat base and upstanding walls, one of said walls having its upper portion overlying the base and provided at its juncture with the top of the urinal with a cut-away portion forming an upstanding emptying nozzle, a portion of said nozzle overlying the said end wall at the base to facilitate in emptying said urinal. 115

9. A urinal of sheet metal having a relatively broad flat base of rectangular formation and having an upstanding end wall inclining outwardly and oppositely disposed upwardly extending end walls inclining inwardly, and two opposed side walls inclining inwardly and joining the two end walls to provide a closed top of somewhat curved formation, the two side walls having concave faces adjacent the first mentioned wall, said 125

top of the urinal at its juncture with the first mentioned end wall being open to provide a discharge nozzle, said discharge nozzle lying substantially in the plane of the top of said urinal.

5 In witness whereof, we have hereunder subscribed our names.
